UNITED STATES PATENT OFFICE.

WALTER S. SLANGERUP, OF OMAHA, NEBRASKA, ASSIGNEE TO PERFECTION DOOR MOUNTING HINGE COMPANY, OF OMAHA, NEBRASKA.

DOOR MOUNTING.

Application filed June 23, 1923. Serial No. 647,382.

To all whom it may concern:

Be it known that I, WALTER S. SLANGERUP, a citizen of the United States, residing at Omaha, in the county of Douglas and State of Nebraska, have invented certain new and useful Improvements in a Door Mounting, of which the following is a specification.

This invention relates to an improvement in that class of door mountings wherein 10 pintles are employed which project vertically from the top and bottom of a door for bearings in sockets, said mounting being found to be of particular advantage for use in connection with garage doors where the 15 floors or thresholds are constructed of cement or concrete.

The invention is illustrated and described in connection with a garage door, and has for one of its objects to provide such a 20 construction that each vertical wing-plate will be disposed in line with the longitudinal axis of its pintle and will be provided with a bearing-head upon which the door may have a support and which will permit the 25 door to be mounted upon either side of the plate. Another object is to provide such a construction that no chamfering of a door will be required, and that a wing-plate, bearing-head and pintle will consist of a 30 single structure, so that the door may be mounted upon the bearing-heads of the wing-plates after the latter have been disposed with their pintles engaging in the 35 sockets. Another object is to provide a construction consisting of few and simple parts so that manufacture may be convenient and economical.

With the foregoing objects in view the invention presents a novel construction, combination and arrangement of parts, as described herein and claimed, and as illustrated in the accompanying drawing, wherein,—

Fig. 1 is a broken view showing a door mounted by use of the device. Fig. 2 is a 45 broken away end view of a door with the device mounted thereon, the socket or sleeve being in section. Fig. 3 is a side view of the parts shown in Fig. 2. Fig. 4 is a sectional view on line 4—4 of Fig. 3.

Referring now to the drawing, the invention is described in connection with a wall 5 and a cement or concrete floor or base 6. Numerals 7 and 8 indicate a pair of vertically disposed sockets or sleeves used for mounting a single door 12, each sleeve preferably

being provided with a head-member or flange *a*, preferably of disc-shape, the sleeve 7 being mounted in the cement or concrete 6 near the wall, with the top of its flange *a* disposed in the plane of the floor-surface, 60 the sleeve 8 being inverted and mounted in the cross-beam or other support 9.

I provide a pair of wing-plates 10, each being provided with a pintle 11 and having a bearing-head or flange *b* preferably of 65 disc-form at the junction of the plate and pintle. While the wings 10 may have any suitable shape, they preferably consist of prongs for suitably supporting the door when secured thereto. These prongs may 70 have any suitable length, depending upon the width of a door, and their particular shape is not material.

In operation, after the wing-plates have been disposed with their pintles engaging 75 in the sleeves, the door is placed in engagement with the disc-shaped heads *b* at one of the sides of the wing-plates, and by use of keepers *c* the door is secured thereto.

Among some of the advantages to be derived by use of the invention it may be 80 stated that each pintle and bearing-head *a* is a part of a wing, and therefore manufacture may be convenient and economical, and stresses on the door will be adequately resisted by the engagement of the pintles in 85 the sleeves or sockets. It will be noted that no stresses occasioned by the weight of the door will be delivered to the wall 5, and that no casings for doors will be required since 90 the door swings from the pintles at the top and bottom. The engaging heads *a* and *b*, as described, are of particular advantage in 95 supporting doors of unusual weight, and since each wing is disposed in the vertical plane of a pintle the door may be mounted upon the outer or inner side of a wing-plate, as may be selected, thereby permitting the door to swing inwardly or outwardly without changing the construction.

While I have described exact details, I 100 do not wish to be understood as limiting myself in this respect, and changes in size, form, proportion and minor details may be made, said changes being determined by the scope of the invention as claimed.

I claim as my invention,—

1. In a door mounting, a lower vertical sleeve, an upper vertical sleeve each being provided with a flange, a pair of wing-plates 110

- each being provided with a pintle for engaging in a sleeve and having a flange extending outwardly of its sides at its junction with the pintle for engaging the flange of the sleeve, each wing-plate being disposed in line with the longitudinal axis of its pintle to permit the door to engage a selected side of a wing-plate in engagement with the flange thereof.
- 10 2. In a door mounting, a lower vertical sleeve, an upper vertical sleeve, a pair of wing-plates each having a pintle for engaging in a sleeve and having a flange projecting from its sides at its junction with the pintle for engaging a sleeve, each wing-plate being disposed in line with the longitudinal axis of its pintle to permit the door to engage a selected side of a wing-plate in engagement with the flange thereof.
- 15 3. The combination with an upper sup-

port and a base support and a door having a vertical pintle projecting above its top for a pivotal mounting in the upper support, of a vertically disposed sleeve in the base support, a wing-plate provided with a pintle for engaging in the sleeve and having a disc-shaped flange at its junction with the pintle for engaging said sleeve, said wing-plate and the longitudinal axis of its flange being disposed in line with the longitudinal axis of its pintle to permit engagement of the door with said flange and a selected side of the wing-plate.

In testimony whereof, I have affixed my signature in presence of two witnesses.

WALTER S. SLANGERUP.
